UNITED STATES PATENT OFFICE

HARRY L. FINK, OF NEW YORK, N. Y.

TERRAZZO STRIP

Application filed April 12, 1928. Serial No. 269,340.

The invention relates to metal strips used to separate sections or areas of different colors or compositions, of walls or floors of plastic material, usually concrete mixtures; or to produce surface "patterns" in such floors, these structures being usually called "terrazzo" or "terrazzo mosaic". The strips are therefore conveniently identified as "terrazzo strips".

10 The general object is to provide an improved strip having a wide upper surface, which produces wide metal zones or stripes separating the tile or mosaic areas, and defining the surface "pattern". These strips as heretofore made are usually of sheet metal of moderate thickness, whose upper edges provide only narrow surface lines or stripes.

15 It will be noted that in each case the head or top bar is so constructed as to form a rabbet for the base strip and also that such head projects, opposite the rabbet over the portions 2. This rabbet has a flat side resting against the side of the base strip and a shoulder resting on the top edge of said base strip.

20 A more particular object is to provide the desired wide top surface as a part of an originally-separate top or "head" strip, of substantial cross-section, permanently secured to the main or "body" strip of sheet metal, as by spot welding. Thus a substantial economy of material is effected, and the upper portion of the complete strip has increased strength and rigidity.

25 The top or head strip preferably has a dependent portion or face overlapping and welded to an upper marginal face of the body strip, and a horizontal flange or shoulder abutting the upper edge of the body strip.

30 The characteristics and advantages of the invention are further sufficiently explained in connection with the following detail description of the accompanying drawing, which shows representative embodiments.

35 After considering these examples, skilled persons will understand that many variations may be made without departing from the principles disclosed, and I contemplate the employment of any structures that are properly within the scope of the appended claims.

Fig. 1 is a combined sectional and perspective view of a terrazzo strip, embodying the invention in one form.

Figs. 2 and 3 are similar views of modified structures.

55 The main or body strip 1 is of sheet metal (usually brass) of moderate thickness, as usual. It may have any suitable formations to form a bond with the concrete material, such as the integral bowed strips 2, produced by punching or pressing operations. The upper edges 3 of these strips may in some cases define the upper surface 4 of the lower or base layer 5 of plastic composition, in which the lower part of the body strip 1 is 60 embedded, the upper or finishing layer 6 of one or a variety of compositions or colors being then poured between the partitions provided by the upper portions of the strips.

65 The upper portion or "head" of the complete strip consists of an originally separate strip or bar 7 of substantial cross-section (this being also usually brass). The sectional form of this bar may vary. Thus in Fig. 1 it is of nearly oblong cross-section, having 70 one side cut away below the top to form an inset face 8 fitting against the upper margin of strip 1, and a shoulder 9 overlying the upper edge of strip 1. In Fig. 2 bar 7^a is of T-section, the vertical flange 10 lying against 75 the face of strip 1, and one of the top flanges 11 overlying and projecting beyond the upper edge of the base strip. In Fig. 3, the sectional form of bar 7^b is the same as that of bar 7 of Fig. 1, with the addition of an upper 80 flange 12.

85 In any of its forms, the top bar or head has a flat upper face 15 of substantial width, greater than that of the base strip, to provide a relatively wide visible metallic strip or band 90 on the wall or floor surface, when the complete strip is "set" in the plastic structure in the usual way.

95 The head or top bar may be connected to the body strip in any suitable way. Preferably it is secured by spot-welding, these welds 20 being made at suitable intervals, to secure together the dependent flange portion of the head and the upper margin of the base strip.

I claim:

1. A terrazzo strip, comprising a base strip of sheet metal of moderate thickness and an operatively-integral metal head of relatively thick cross-section having a top surface of substantial width, greater than that of the base strip, said head having a rabbet running along one lower edge of the head and into which the upper part of the base strip fits with an upper side portion against the side of the rabbet and its top edge engaging the top of said rabbet.

2. A terrazzo strip, comprising a base strip of sheet metal of moderate thickness and an originally-separate metal head of substantial thickness, having a wide top surface, and permanently secured to an upper portion of the base strip, said head having a rabbet running along one lower edge of the head and into which the upper part of the base strip fits with an upper side portion against the side of the rabbet and its top edge engaging the top of said rabbet.

3. A terrazzo strip, comprising a base strip of sheet-metal of moderate thickness and an originally-separate metal head of substantial thickness, having a wide top surface, and permanently secured by welding to an upper portion of the base strip, said head having a rabbet running along one lower edge of the head and into which the upper part of the base strip fits with an upper side portion against the side of the rabbet and its top edge engaging the top of said rabbet.

4. A terrazzo strip, comprising a base strip of sheet metal of moderate thickness and an operatively-integral metal head of relatively thick polygonal cross-section having a top surface of substantial width, greater than that of the base strip, the head having a portion overlying the upper edge of the base strip, said head having a rabbet running along one lower edge of the head and into which the upper part of the base strip fits with an upper side portion against the side of the rabbet and its top edge engaging the top of said rabbet.

5. A terrazzo strip, comprising a base strip of sheet metal of moderate thickness and an originally-separate metal top bar of substantial thickness, said top bar having a rabbet running along one of its lower edges, the upper portion of the base strip having its side surface abutting against the side of the rabbet, and means for permanently securing the abutting portions of said bar and base strip to each other.

6. A terrazzo strip comprising originally-separate upper and lower metal sections, one of said sections being formed to present surfaces substantially perpendicular to each other in planes which form a reentrant angle into which the other section may be assembled by sidewise motion, and the other section having an edge contacting with one of said surfaces and a side contacting with the other of said surfaces; and means for permanently securing the two sections together.

7. A terrazzo strip having an uninterrupted straight upper edge; the strip comprising originally-separate upper and lower metal sections, one of said sections being formed to present surfaces substantially perpendicular to each other in planes which form a reentrant angle into which the other section may be assembled by sidewise motion, and the other section having an edge contacting with one of said surfaces and a side contacting with the other of said surfaces; means for permanently securing the two sections together; and anchoring means extending outwardly from one side of the lower section.

8. A terrazzo strip comprising originally-separate upper and lower metal sections, one of said sections being formed to present substantially flat surfaces positioned in two planes which form a reentrant angle that is substantially a right angle, and the other of said sections having a side surface and an edge surface forming an exterior angle that is also substantially a right angle, the two sections being assembled with the exterior angle of one section nesting with the reentrant angle of the other section; and means for permanently securing the two sections together.

9. A terrazzo strip comprising originally-separate upper and lower sections, the lower section being formed from sheet metal of moderate thickness and the upper section being metal of greater thickness, one of said sections being formed to present substantially flat surfaces positioned in two planes which form a reentrant angle that is substantially a right angle, and the other of said sections having a side surface and an edge surface forming an exterior angle that is also substantially a right angle, the two sections being assembled with the exterior angle of one section nesting with the reentrant angle of the other section; and means for permanently securing the two sections together.

10. A terrazzo strip comprising originally-separate upper and lower sections, the lower section being formed from sheet metal of moderate thickness and the upper section being metal of greater thickness, one of said sections being formed to present substantially flat surfaces positioned in vertical and horizontal planes which form a reentrant angle that is substantially a right angle, and the other of said sections having a side surface and an edge surface forming an exterior angle that is also substantially a right angle, the two sections being assembled with the exterior angle of one section nesting with the reentrant angle of the other section; and means for permanently securing together the contacting vertical surfaces of the two sections.

11. A terrazzo strip having uninterrupted straight upper and lower edges; the strip comprising originally-separate upper and lower sections, the lower section being formed from sheet metal of moderate thickness and the upper section being metal of greater thickness, one of said sections being formed to present substantially flat surfaces positioned in two planes which form a reentrant angle that is substantially a right angle, and the other of said sections having a side surface and an edge surface forming an exterior angle that is also substantially a right angle, the two sections being assembled with the exterior angle of one section nesting with the reentrant angle of the other section; means for permanently securing the two sections together; and anchoring means extending outwardly from one side of the lower section.

12. A terrazzo strip comprising a base strip of sheet metal of moderate thickness, an originally-separate metal top bar of substantial thickness having a straight uninterrupted upper edge, said top bar having a rabbet running along one of its lower edges whereby the lower portion of the top bar is of lesser thickness than the upper portion, means for securing the base strip to the thinner portion of the top bar, and anchoring means projecting outwardly from the base strip.

In testimony whereof I affix my signature.
HARRY L. FINK.
